PAUL MACGAHAN, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL PROTECTIVE DEVICE.

1,312,796.

Specification of Letters Patent. Patented Aug. 12, 1919.

Application filed July 6, 1917. Serial No. 178,920.

To all whom it may concern:

Be it known that I, PAUL MACGAHAN, a citizen of the United States, and a resident of Pittsburgh, in the county of Allegheny and State of Pennsylvania, have invented a new and useful Improvement in Electrical Protective Devices, of which the following is a specification.

My invention relates to electrical protective devices and particularly to means for protecting parallel-connected transmission circuits.

One object of my invention is to provide means for protecting parallel-connected transmission circuits that are traversed by different values of current.

Another object of my invention is to provide a single relay for the corresponding ends of a system of the above-indicated character that shall be adapted to selectively control the circuit interrupters of the parallel-connected circuits.

Heretofore, it has been the practice to protect parallel-connected transmission circuits by operatively connecting the same together and providing relays across the equal-potential points of the connecting means. Such devices will not function properly unless the loads on the various parallel-connected circuits are normally equal.

In view of the above, I provide means whereby a plurality of parallel-connected circuits that are traversed by different values of current may be protected. In practising my invention, I connect a resistor or auto transformer across the connecting means between the corresponding conductors of the parallel-connected circuits and so adjust the same that equal-potential points will obtain irrespective of the normal variation in the energy traversing the various circuits. The current winding of a single-phase reverse energy relay is connected to the equal-potential points and adapted to selectively control the circuit interrupters in the several parallel-connected circuits.

In the accompanying drawings, Figure 1 is a diagrammatic view of an electrical circuit embodying my invention, and Fig. 2 is

cuit embodying a modified form of my invention.

A generator 1 is connected to bus bars 2 and 3 which are connected through two parallel-connected transmission or feeder circuits 4 and 5 to a load circuit 6.

The transmission circuit 4 comprises two conductors 7 and 8 that are provided with circuit interrupters 9 and 10 at the respective ends thereof. Similarly, the circuit 5 comprises two conductors 11 and 12 that are provided with circuit interrupters 13 and 14 at the respective ends thereof. It may be assumed, for purposes of explanation, that the circuit 4 is of less impedance than the circuit 5 and, consequently, is traversed by relatively more current. The circuits 4 and 5 are provided with similar current transformers 15 and 16, and 17 and 18, respectively, at the respective ends thereof. One terminal of the transformer 15 is connected to one terminal 19 of a resistor 20 the other terminal 21 of which is connected to one terminal of the transformer 17. The other terminal of the transformer 17 is connected to the terminal 19 of the resistor 20. The other terminal of the transformer 15 is connected to an intermediate point 22 of the resistor 20. Similarly, one terminal of the transformer 16 is connected to one terminal 23 of a resistor 24 the other terminal 25 of which is connected to one terminal of the transformer 18. The other terminal of the transformer 18 is connected to the terminal 23 of the resistor 24, and an intermediate terminal 26 of the resistor 24 is connected to the other terminal of the transformer 16.

The intermediate terminal 26 of the resistor 24 is so located that the current through that portion of the resistor between the terminals 23 and 26 equals the difference between the currents in the circuits 4 and 5. That is, the drop in potential across this portion of the resistor must be equal to the drop in potential through the remaining portion thereof and of such sign that the total drop in potential between the terminals 23 and 25 is zero. Similarly, the terminal 22 of the resistor 20 is so located that the drop in potential between the terminals 19 and 21 is zero.

and 21 is zero. Thus, it will be readily seen that a number of equal-potential points will obtain across the cumulatively-connected circuits 27 and 28 between the respective 5 transformers.

A reverse-energy relay 29 and an overload relay 30 are provided for controlling the circuits of the trip coils 31 and 32 of the circuit interrupters 10 and 14, respectively, 10 and a reverse-energy relay 33 and an overload relay 34 are provided for controlling the circuits of the trip coils 35 and 36 of the circuit interrupters 9 and 10, respectively. The relays 29 and 33 severally comprise a current winding 37, a potential winding 38, that is connected across the conductors 7 and 8 or the bus bars, a magnetizable core member 39, an armature 40, a movable contact member 41, and stationary contact 15 members 42 and 43. The relays 30 and 34 severally comprise a current winding 44, a magnetizable core member 45, an armature 46, a movable contact member 47, and a stationary contact member 48. The current 20 windings 37 and 44 of the relays 29 and 30 are connected in series across the equal-potential points of the circuit 28 and the current windings 37 and 44 of the relays 33 and 34 are connected in series across the equal- 25 potential points of the circuit 27.

Since the current windings of the relays are connected across normally equal-potential points and, since the resistors 20 and 24 maintain these points of equal potential, 30 irrespective of the normally unequal division 35 of the energy through the circuits 4 and 5, it will be seen that the contact members of the respective relays are normally held out of engagement. However, if a fault, such 40 as a ground, occurs in the circuit 5, the current traversing the same will so change as to upset the normal circulation of current in the circuits 27 and 28 and, consequently, the condition of equal-potential points therein. 45 This will cause the relay 29 to effect engagement between its contact members 41 and 43, and, if the current traversing the circuit 5 is of a predetermined value, the relay 30 will cause its contact member 47 to 50 engage its stationary contact member 48, thus effecting the energization of the trip coil 32 from a source 49 of electromotive force to thereby trip the circuit interrupter 14. Similarly, the reversal of the current 55 in the circuit 5 will effect the opening of the circuit interrupter 13.

If a ground obtains in the circuit 4, the 60 relays 29 and 33 will cause their movable contact members 41 to engage their stationary contact members 42, and, if the overload is of a sufficient value, the relays 30 and 34 will cause their contact members 47 and 48 to be engaged and the trip coils 31 and 35 to be energized to trip the circuit 65 interrupters 10 and 9. Thus, the relays 29

and 33 are adapted to selectively trip their respective circuit interrupters in accordance with the position of the fault on the circuits to be protected.

In Fig. 2 of the drawings, I have shown 70 a modification of my invention wherein I have substituted an auto transformer 50 for the resistor 24 shown in Fig. 1 of the drawings. That is, the transformer 16 is connected to points 51 and 52 thereon and the 75 transformer 18 is connected to points 53 and 52 thereon. The current winding 27 of the reverse-energy relay is connected to equal-potential points of a circuit 54, thus constituted, and is adapted to selectively control the tripping of the interrupters 10 and 14, substantially as hereinbefore set forth. In this modification of my invention, I have shown the relay 29 alone controlling the trip coils, 31 and 32, because, in some instances, 80 it is not essential that an overload relay be employed. It will, of course, be apparent that the auto transformer 50 is employed for the same purpose as the resistors 20 and 24, as shown in Fig. 1 of the drawings. In other 85 words, it is employed to maintain equal-potential points in the circuit 54, irrespective of the normal difference in energy traversing the circuits 4 and 5.

My invention is not limited to the single-phase system illustrated, as it is applicable to any number of phases, and various modifications may be made therein without departing from the spirit and scope of the invention as set forth in the appended claims. 100

I claim as my invention:

1. In an alternating-current system of distribution, the combination with parallel-connected feeder conductors carrying different values of current, and a current transformer 105 for each conductor, of a resistor connected across one transformer and a portion thereof connected across another transformer, said resistor being so connected that equal-potential points are provided on the connecting 110 means.

2. In an alternating-current system of distribution, the combination with parallel-connected feeder conductors carrying different values of current, and a current transformer 115 for each conductor, of a resistor so connected to the transformers that equal-potential points are provided on the connecting means.

3. In an alternating-current system of distribution, the combination with parallel-connected feeder conductors carrying different values of current, and a current transformer for each conductor, of an energy-absorbing means, means for connecting the 125 said energy-absorbing means across one transformer and a portion thereof across another, whereby equal-potential points are provided on the connecting means.

4. The combination with parallel-con- 130

5 nected feeder conductors carrying different values of current, circuit interrupters there-
for, a transformer connected to each feeder conductor, and means for cumulatively connect-
ing the transformers together, of means
5 so connected across the said connecting means as to provide equal-potential points in the said connecting means.

10 5. The combination with parallel-con-
nected feeder conductors carrying different values of current, circuit interrupters there-
for, a transformer connected to each feeder conductor, and means for cumulatively connect-
ing the transformers together, of a re-
15 sistor so connected to the said connecting means as to provide equal-potential points on the said connecting means.

20 6. The combination with parallel-con-
nected feeder conductors carrying different values of current, and a transformer con-
nected to each conductor, of a resistor, means for connecting the resistor across the terminals of one transformer, and means for connect-
25 ing a portion of the resistor across the terminal of another transformer whereby equal-potential points are produced in said first mentioned connecting means.

30 7. The combination with two parallel-con-
nected feeder conductors carrying different values of current, circuit interrupters there-
for, a transformer connected to each feeder conductor, and means for operatively connect-
35 ing the transformers at the correspond-
ing ends of the conductors together, of means

so connected to the connecting means as to 35 provide equal-potential points therein, and a single relay connected across the equal-potential points for selectively controlling the interrupters.

8. The combination with two parallel- 40 connected feeder conductors carrying different values of current, a circuit interrupter for each conductor, and a transformer connected to each conductor, of means for so connect-
ing the transformers together that equal-pot- 45 ential points are provided on the connect-
ing means, and a single relay having its cur-
rent winding connected across the equal-pot-
ential points and its potential winding con-
nected to the feeder conductors for selec- 50 tively controlling both interrupters.

9. The combination with two parallel-con-
nected feeder conductors carrying different values of current, a circuit interrupter for each conductor, a series transformer for each 55 conductor, and means for cumulatively connect-
ing the same together, of means so connected to the said connecting means that equal-potential points are provided therein, and a single reverse-energy relay having its 60 current winding connected across the equal-potential points and its potential winding connected to the feeder conductors for selectively controlling both interrupters.

In testimony whereof, I have hereunto 65 subscribed my name this 29th day of June 1917.

PAUL MacGAHAN.
